UNITED STATES PATENT OFFICE

2,622,557

MACHINE FOR SPREADING GLUE ON THE EDGES OF BOARDS

Joe Marcantel, Oakdale, La., assignor to Hillyer Deutsch Edwards, Inc., Oakdale, La., a corporation of Louisiana

Application October 21, 1948, Serial No. 55,763

3 Claims. (Cl. 118—239)

1

The present invention relates to a device for spreading liquid, and is particularly concerned with a device of the character under consideration which is specifically intended for spreading liquid glue upon the edges of boards carried past a spreading station by conveyor means. The primary object of the invention is to provide means whereby glue or other liquid may be more effectively spread on work carried past the station. A further object of the invention is to improve the construction and operation of a liquid spreading machine as a whole. A further object of the invention is to mount a liquid spreading wheel upon bearings spaced axially from each other to a substantial extent, said bearings being independently spring supported, whereby the attitude, as well as the position, of the liquid spreading wheel may vary in response to variations in pressure exerted upon it peripherally. Still further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a perspective view of a liquid spreading machine embodying the present invention;

Fig. 2 is a perspective view of the vat means, the spreader wheel, and the directly associated parts, upon a somewhat enlarged scale;

Fig. 3 is a fragmentary enlarged perspective view of the mounting for a presser roll;

Fig. 4 is a fragmentary plan view of a kicker assembly, forming a part of the machine; and

Fig. 5 is an enlarged end elevation of a detail of the axle support.

Referring more particularly to the drawings, it will be seen that I have illustrated a vat means indicated generally by the reference numeral 10 and comprising an outer container 11 in which is received a receptacle 12 for a liquid to be spread. The invention is particularly adapted to the spreading of glue, and has been so illustrated and will be so described; although it will be apparent that the invention is also applicable to the spreading of any other reasonably viscous liquid.

In the illustrated embodiment of the invention, the receptacle 12, partially filled with glue or other liquid, is supported in the container 11 upon hangers 13 and 14, the walls of the receptacle being substantially spaced from the walls of the container, whereby any liquid which is splashed from the receptacle will be retained in the container. Two blocks 15 and 16 are removably secured, by any suitable fastening means, to the outer surfaces of the opposed walls 17 and

2

18 of the container 11. Said blocks 15 and 16 are identical, and therefore only one will be described in detail. Each block is formed with a trackway 19 which, in the illustrated embodiment of the invention, is rectilinear and vertically arranged. In the illustrated embodiment of the invention, the trackway comprises facing dovetailed grooves 20 and 21 formed in the spaced parallel, vertically arranged walls of the block 15. The block 15 extends above and below the upper edge of the wall 17 of the container 11 with which it is associated.

An axle 22 supports the spreader wheel 23 and has a substantial axial extent in opposite directions from said wheel. At points oppositely spaced axially from the wheel, the bearing elements 24 and 25 engage the shaft 22 to support the same; and said bearing elements are reciprocably mounted in the trackways of the respective blocks 15 and 16. A coiled spring 26 is confined between the bottom of the trackway 19 and the bearing 24, resiliently supporting said bearing element. The bearing 25 is similarly supported in block 16 upon a spring similar to the spring 26; and it will be obvious that the two bearings 24 and 25 are independently reciprocable in the trackways of the blocks 15 and 16, the engagement of the bearings in the dovetailed grooves of the block trackways being sufficiently loose to permit tilting of the axle 22 out of the horizontal, thereby changing the attitude of the wheel 23, as well as its position.

A bracket 27 is secured to the bearing element 25 by a screw 28 or the like; and, near its opposite end, said bracket is provided with an elongated slot 29 in which engages a clamping screw 30 for securing to said bracket a doctor 31 which adjustably straddles the wheel 23 to scrape liquid from its axial ends and to limit the depth of the film of liquid on the periphery of said wheel.

A work support comprising separate elements 32 and 33, terminating adjacent the portion of the periphery of the wheel 23 which projects above the walls of the vat means 10, is disposed in a plane parallel with, but spaced below, the horizontal plane tangent to the uppermost portion of the periphery of the wheel. The springs 26 normally support the bearing elements 24 and 25 in such positions that the axle 22 is horizontal and the uppermost portion of the periphery of the wheel 23 is located substantially above the plane of the work support. Adjacent the wheel 23, and upon spaced vertical axes, are mounted two sprockets 34 and 35 about which is trained a chain conveyor 36. A channel mount 37 is secured adjacent that run of the conveyor 36 which passes the wheel, and provides mountings for a plurality of pivots 38 with each of which is associated a presser roller 39. The precise construction of the presser rollers is best illus-

trated in Fig. 3, in which it will be seen that a barrel 40 is mounted to oscillate about the axis of each pivot 38, said barrel carrying a finger 41 on the outer end of which is hung a journal member 42 supporting the roller 39. An ear 43 on the barrel 40 provides a stud 44 over which is sleeved one end of a coiled spring 45, the opposite end of which is sleeved upon a projecting end of a screw 46, and bears against an abutment 47 carried by said screw. Each screw 46 threadedly penetrates a tapped opening 48 in the channel 37, whereby adjustment of the screw 46 will adjust the degree of compression of the associated spring 45. The rollers 39 are thus resiliently urged toward the adjacent run of the conveyor chain 36.

Work will be fed to the machine at the right-hand end of Fig. 1, being inserted between the conveyor and the first presser roller 38; and will be carried along between the conveyor and said presser roller, while supported upon the work support 32. The illustrated arrangement is particularly adapted to the application of glue to an edge of relatively narrow boards. As each board is carried past the wheel 23, its lowermost edge will contact the periphery of said wheel at a level below the horizontal plane tangent to the wheel periphery. The board being gripped between the conveyor and the presser rollers 39, a downward pressure will be exerted upon the wheel 23 as the board moves forwardly. Since the wheel is supported upon the axle 22 whose opposite ends are independently carried by the spring-supported bearing elements 24 and 25, the wheel, axle and bearings will thereby be depressed, against the tendency of said springs.

Now, if the wheel-engaging edge of the board is longitudinally wavy, it will be seen that the springs 26 will cause and permit the wheel to move upwardly and downwardly to follow the waves in the edge of the board. If the wheel-engaging edge of the board is not square with the board surfaces engaging the conveyor and the presser rollers, the independent movability of the bearing elements 24 and 25 will permit the wheel to change its attitude to maintain contact throughout the width of the board edge, whereby glue will be spread evenly over the edge of the board in spite of imperfections in said edge.

Adjacent the sprocket 35, a bracket 49 projects from the frame element 50 to provide a pivot point 51 upon which is pivotally mounted a lever 52 carrying, at its outer end, a shoe 53 which will engage work emerging from the last presser roller 39. A spring 54 has one end connected to the opposite arm of lever 52 and its other end anchored at 55 on the frame element 50, the effect of said spring being to urge the shoe 53 to a position laterally beyond the plane of the adjacent run of the conveyor 36. Thus, as a piece of work emerges into contact with the shoe 53, it will swing the lever 52 in a clockwise direction against the tendency of the spring 54. As soon as the trailing end of the work piece leaves the last presser roller 39, the spring 54 will swing the lever 52 in a counter-clockwise direction to tilt that work piece, throwing it off its edge and onto one face. A strap 56, carried by the frame element 50, is formed to provide a stop shoulder 57 against which the lever 52 is normally held by the spring 54.

Preferably the axle 22 will carry a pulley 58 whereby said axle may be driven, through a belt 59, from any suitable power source.

I claim as my invention:

1. In a liquid-spreading machine, vat means

including a receptacle for liquid, a wheel, an axle for said wheel, two bearing elements respectively associated with said axle at points oppositely axially spaced from said wheel, a guideway for each of said bearing elements, comprising a block providing a trackway slidably receiving its associated bearing element, said blocks being removably secured to the outer surfaces of opposed walls of said vat means and projecting above said walls, and spring means confined between the bottom of each trackway and its associated bearing element, said spring means normally supporting said axle in horizontal position above said walls with a portion of the periphery of said wheel disposed within said receptacle below the normal level of liquid in said receptacle.

2. In a liquid-spreading machine, vat means including a receptacle for liquid, a wheel, an axle for said wheel, two bearing elements respectively engaging said axle at points oppositely axially spaced from said wheel, a guideway for each of said bearing elements, said guideways projecting above opposed walls of said vat means and each providing a substantially vertically-extending track engaging its associated bearing element to guide reciprocatory movement of such bearing element, spring means for each of said bearing elements normally supporting said axle in horizontal position above said walls with a portion of the periphery of said wheel disposed within said receptacle below the normal level of liquid in said receptacle, a doctor straddling said wheel in a region above the level of liquid in said vat means, and means movable with one of said bearing elements and supporting said doctor.

3. In a liquid spreading machine, vat means including a receptacle for liquid, a wheel, an axle for said wheel, two bearing elements respectively engaging said axle at points oppositely axially spaced from said wheel, a guideway for each of said bearing elements, said guideways projecting above opposed walls of said vat means and each providing a substantially vertically-extending track engaging its associated bearing element to guide reciprocatory movement of such bearing element, spring means for each of said bearing elements normally supporting said axle in horizontal position above said walls with a portion of the periphery of said wheel disposed within said receptacle below the normal level of liquid in said receptacle, each of said bearing elements being rockable, relative to its track, about a horizontal axis perpendicular to said axle, a work support adjacent said wheel and located in a plane substantially parallel with, but below, the horizontal tangent to the uppermost portion of the periphery of said wheel, and means for moving a work piece past said wheel in contact with the periphery thereof while holding the same substantially in the plane of said work support.
